UNITED STATES PATENT OFFICE.

IVAN C. FREY, OF YORK, PENNSYLVANIA.

BRICKMAKING-MACHINE.

1,301,048.

Specification of Letters Patent. Patented Apr. 15, 1919.

Application filed December 1, 1915. Serial No. 04,418.

To all whom it may concern:

Be it known that I, IVAN C. FREY, a citizen of the United States, residing in the city of York, county of York, and State of Pennsylvania, have invented certain Improvements in Brickmaking-Machines, of which the following is a specification.

My invention is a machine designed particularly for making soft clay brick, and the 10 principal objects of my invention are to provide a machine of simple construction which will produce perfect bricks in large quantities at low cost by a continuous automatic operation, without waste of material and 15 with elimination of manual labor.

In the preferred form of my invention, clay supplied to a tempering chamber is automatically worked and fed into a hopper from which it is discharged through a die 20 into molds and compressed therein by the action of a reciprocating ram or plunger, the compression of the clay in the hopper acting to depress a strike knife which removes surplus clay from bricks passing 25 thereunder and returns the excess material to the hopper. The molds are moved about a circular housing by toothed wheels and into position to be struck by a vibratory knocker which loosens the clay from the 30 molds' walls so that when the molds are inverted the bricks drop out onto a counterbalanced table by which they are deposited on a conveyer and carried to a drying room. The empty molds are then automatically 35 sanded and returned to position for filling, surplus sand falling from the molds being collected and returned to the sanding device.

The characteristic features of my invention will more fully appear from the following 40 specification and the accompanying drawings in illustration thereof.

In the drawings, Figure 1 is a side elevation of a machine embodying my improvements; Fig. 2 is a longitudinal sectional view 45 thereof; Fig. 3 is an end view thereof; Fig. 4 is an elevation of the strike knife supporting mechanism, with parts broken away for better illustration of the die; Fig. 5 is a transverse sectional view on the line 5—5 50 of Fig. 2; and Fig. 6 is a perspective view of a mold used in my machine.

As shown in the drawings, my machine comprises a frame having standards 1 and 2 which support a tempering trough 3, and 55 a housing 4 in which are journaled trunnions 6, 6' of sprocket wheels 5, 5'.

A driving shaft 8, revolved in any suitable manner, is journaled in bearings in the standard 2 and has fixed thereto a pinion 9 by which it drives, through the idlers 10 60 and 11, a gear 12 fixed on a shaft 13, the latter being journaled in a bearing 14 fixed on the front of the trough 3 and in the bearings 15 carried by the standard 2. The shaft 13 extends longitudinally through the tempering trough and has fixed thereto, within the trough, a sectional casting 16 carrying a plurality of angularly disposed knives 17 and the semi-circular wipers 18, which feed the clay forward and into a hopper or press 70 box 19 in the front of the trough.

The hopper 19 has a yielding wall 20 formed by a curved plate fixed on a shaft 21 journaled in bearings in the trough, one end of the shaft passing through a side of the 75 trough and having fixed thereon an arm 22. The arm 22 has connected therewith a spring 24 connected to the trough and permitting the plate 20 to yield when the pressure in the hopper reaches a predetermined point. 80

A door or plate 25, secured to the front of the trough, and a bar 26, fixed to the frame by rods 26', provide guides for a vertically movable plate 27 slidably engaged to the door 25 by the turn buttons 28 thereon. The 85 plate 27 has fixed thereto a pressure bar 29 provided with a knife 30, and the front of the trough 3 adjacent the door 25 is cut away to permit the clay in the hopper 19 to impinge upon the knife and enter the recess 90 19' between the door 25 and the pressure bar 29, whereby pressure on the clay in the hopper acts through the pressure bar to depress the knife 30.

A ram or plunger 31 is connected by a 95 rod 33 with a walking beam 32, the walking beam being pivoted to a rocking support 34 on the trough and reciprocated, to reciprocate the plunger, by a pitman 34 pivotally connected with the wrist pin 35' of a crank 100 35 fixed on the shaft 13, the plunger being guided by the front of the trough and the guides 36.

A die 37, disposed in the outlet 38 from the hopper, contains the partitions 37' and 105 has openings 37'' in its face so that clay pressed therethrough by the action of the plunger 31 may act freely on the pressure bar 29 to depress the knife 30 and to permit the return of surplus clay struck from the 110 bricks directly to the hopper.

A plurality of molds 38 are introduced

into the housing 4 through the hinged section 4^a thereof and contain recesses 39 for the reception of teeth of the sprocket wheels 5, 5', by which the molds are movable within 5 the housing so as to be brought in sequence beneath the die, the molds being supported and guided intermediate of the sprockets by flanges 4' and 4'' of the housing. A roller 42, journaled in the housing 4 beneath 10 the plunger, acts as an anvil for supporting the mold which is being filled against the blow of the plunger.

The trunnion 6' has thereon a ratchet wheel 43 provided with teeth 44 adapted to 15 be engaged by a pawl 45 pivoted on the vibrating arm or lever 46 loosely fulcrumed on the trunnion. The pawl lever is oscillated by a pitman 47 connected with an eccentric wrist pin 48 of a sheave 49. This 20 shaft is fixed on a shaft 50 journaled in the frame and revolved from the gear 12 through the gear 51, worm 52, shaft 53, and pinion 54, whereby the molds are given a step by step movement in synchronism 25 with the movements of the plunger.

The housing 4 has fixed thereto, adjacent to the strike knife mechanism, a casing 55 forming a way in which slides a bumper bar 56. A pitman 57 has one end thereof connected with the pin 58 projecting from the bar 56 through the slot 59 in the casing and the other end thereof pivotally connected with the eccentric wrist pin 59^a of a wheel 60 on the shaft 61, the latter shaft being 30 journaled in the frame and rotated through a sprocket 62 thereon from the sprocket 63 on the shaft 8 by the sprocket chain 64.

The bumper 56 is provided with depending arms 65 containing recesses 66 in which 40 are disposed bumper pins 67 movable through apertures in the ends of the arms and provided with collars 68. Springs 69, disposed between these collars and the bases of the recesses 66, press the pins 67 outward 45 so that upon the reciprocation of the bumper bar by the mechanism described they project through apertures 70 in the housing 4 and strike the mold in line therewith cushioned blows to loosen the clay from the walls of 50 the molds.

When a filled mold has passed the bumper and reached the position X, under the hinged sections 4^a of the housing, a pallet 38' is placed thereon, such pallets being 55 held in place during further movement of the molds by bands 71 fixed to cross rods 72 and 72' of the housing.

A table 73 is pivotally connected with levers 74 fulcrumed on bearings 75 on the 60 housing 4, the table being counterbalanced by a weight 76 so as to be normally maintained adjacent to the ends of the bands 71. When, however, a mold passes beyond the bands, the pallet thereon and bricks therein, 65 which have been loosened by the action of

the bumper, drop onto the table, whereupon, the counter-balance being overcome, the table drops and deposits its load upon the conveyer 77, suitably operated by a sheave 78 driven by a belt 79 passing over the 70 sheave 49.

A sand reservoir 80, supported upon a platform 81 of the frame, has a gate 82 normally held closed by a spring 82'. The gate is opened periodically by the engagement 75 therewith of a lug 83 carried by the pitman 47, whereupon sand escapes from the reservoir into a chute 84 which leads to a sander 85 disposed beneath the line of travel of the empty molds. Blades 86 are fixed to a shaft 80 86' journaled in the sander casing and driven through the meshing miter gears 87 and 88, shaft 89, sprocket wheel 90, chain 91 and sprocket wheel 92 on the shaft 61.

It will be understood that, in operation, 85 the clay is comminuted and tempered by the action of the knives of the pug mill and fed into the hopper by the wipers or blades 18. The descent of the plunger 30 forces clay through the die into the mold supported beneath it and against the pressure bar and strike knife, the knife being thereby depressed so as to shear surplus material from and smooth the tops of the bricks passing thereunder. On the upward movement of 95 the plunger, the suction created and the adhesion of the clay draw up the pressure bar and knife, together with the clay sheared thereby, the clay being returned to the hopper through the open faces of the die. 100 When the mold reaches the line of the apertures 70, it is subjected to the cushioned vibratory strokes of the bumper mechanism, whereby the clay is loosened from the mold walls, so that after passing the bands 71, the 105 pallets and bricks will drop onto the table, by which they are deposited on the conveyer. With each movement of the molds, the door of the sand reservoir is opened to allow a proper amount of sand to run down the 110 chute 84 to the sander 85, where it is thrown by the blades 86 into the molds, any surplus sand dropping into the chute and returning to the sander.

Having described my invention, I claim: 115

1. A brick machine comprising a housing having bearings forming an endless path, sprocket wheels journaled in said housing, a plurality of disconnected molds engaged and intermittently movable in said path by 120 said sprocket wheels, means for filling said molds, a way carried by said housing, and a bumper reciprocable in said way transversely to the path of and into contact with a mold engaged by one of said wheels. 125

2. In a brick machine, a housing having a guideway, a plurality of independent molds disposed within the housing, sprocket wheels arranged to engage the molds successively for moving them in the guideway and 130

means for bumping said molds during their engagement by the sprocket wheels.

3. In a brick machine, a housing having a guideway, a plurality of independent molds disposed within the housing, sprocket wheels arranged to engage the molds successively for moving them in the guideway and a reciprocating bumper adapted to move at right angles to the direction of movement of the molds in the guideway for bumping said molds while the latter are engaged by the sprocket wheels.

4. In a brick machine, a housing having a guideway, a plurality of independent molds disposed within the housing, sprocket wheels arranged to engage the molds successively for moving them in the guideway and a reciprocating bumper movable in a direction at right angles to the direction to movement of the molds in the guideway, said bumper being arranged to bump the molds at both ends thereof while the molds are engaged by the sprocket wheels.

5. In a brick machine, the combination of a housing having an endless guideway, a plurality of independent molds disposed in the guideway in parallel relation, each of said molds having a recess, a pair of sprocket wheels having teeth arranged to enter the recesses of the molds successively for moving the molds along the guideway and for preventing an endwise movement of the

molds and means for bumping the molds during the engagement of one of the pairs of sprocket wheels with the molds.

6. In a brick machine, the combination of a housing having an endwise guideway, a plurality of independent molds disposed in the guideway in parallel relation, each of said molds having a recess, a pair of sprocket wheels having teeth arranged to enter the recesses of the molds successively for moving the molds along the guideway and for preventing an endwise movement of the molds and a reciprocating bumper movable at right angles to the movement of the molds and arranged to engage both ends of the molds for bumping the molds while they are engaged by one of the sprocket wheels.

7. In a brick machine, the combination of a housing having bearings forming an endless path, a plurality of disconnected molds movable in said path and partially supported by said bearings and provided with recesses, means for filling said molds with clay, a bumper for striking said filled molds, and a sprocket wheel having teeth arranged to enter the recesses in said molds for holding said molds against the impact of said bumper and for moving them in said way.

In testimony whereof I have hereunto set my name this 27th day of November, 1915.

IVAN C. FREY.
